DISK STORAGE FILE

Clifford B. Bisch, Palo Alto, Edward D. Lucey, Los Gatos, Howard S. Noel, Cupertino, and Peter A. Ronzani, Sunnyvale, Calif., assignors to International Business Machines Corporation, Armonk, N.Y.

Filed Mar. 31, 1970, Ser. No. 22,336

Term of patent 14 years

Int. Cl. D14—02

U.S. Cl. D26—5

FIG.1

FIG. 2

FIG. 1 is a front elevational view of the disk storage file, according to this invention; and

FIG. 2 is a top view of the disk storage file, depicted in FIG. 1.

The side not shown is like the side shown, while the back is conventional.

We claim:

The ornamental design for a disk storage file, as shown and described.
